STREET CAR GRAB HANDLE

Donald E. Johnson, Portland, Oreg.

Application March 15, 1948, Serial No. 14,911

18 Claims. (Cl. 105—354)

1

This invention relates to an improved grab handle for use in street cars, buses, and other vehicles and the like.

Grab handles in public conveyances are subject to much abuse in addition to the stresses imposed by the ordinary use for which they are intended. The forms of such abuse regularly inflicted on public conveyances is almost unlimited in variety and unbelievable in severity. Much substantial and apparently durable equipment has had to be discarded or replaced because it could be cut too easily with a pocket knife or broken or otherwise damaged or taken apart by passengers, either for the purpose of obtaining souvenirs or to satisfy an apparently irrepressible juvenile desire to take things apart. In designing equipment for public use, it has become necessary to render the equipment reasonably incapable of such destruction as may be wrought by pocket knives or pulling, twisting or jerking of the equipment, so that the equipment cannot be damaged or rendered unfit for service by the efforts of a fairly powerful person. Grab handles heretofore used in public conveyances have been particularly susceptible to such abuse and have caused a great deal of expense and annoyance to the operators of the conveyances in maintaining the equipment in serviceable condition.

Objects of the present invention, therefore, are to provide a novel and improved grab handle which not only has ample strength for its intended purpose, but which also is specially designed to withstand the extreme abuse which is to be expected of such equipment on a public conveyance, to provide a grab handle of limited flexibility so that it will yield to twisting and bending stresses without breaking, but which is not long enough or flexible enough to allow it to be wrapped around its support or other object to increase the destructive leverage of any force applied thereto, and to provide a grab handle which, although unusually rugged and durable, is attractive and pleasing to the eye and can be made to harmonize with the interior trim of the vehicle in which it is used.

With these and other objects in view, the invention further resides in the details of construction and arrangement of parts shown in certain preferred embodiments illustrated in the accompanying drawings. It is to be understood, however, that the drawings are not intended to limit the invention as the same may take other forms, all modifications within the scope of the appended claims being included in the invention.

In the drawings:

2

Figure 1 is a perspective view of a grab handle embodying the principles of the invention;

Figure 2 is a fragmentary perspective and sectional view showing a hand grip made entirely of synthetic plastic material, taken on the line 2—2 of Figure 6;

Figure 3 shows a modified form of hand grip similar to Figure 2 but including a steel core, the section being taken on the line 3—3 of Figure 17;

Figure 4 shows another form of hand grip formed from metallic tubing;

Figure 5 is an exploded elevation view showing the component parts of the device illustrated in Figure 1;

Figure 6 is a view of the device of Figure 1 with parts shown in section illustrating the flexibility of the device;

Figure 7 is a perspective view of the anchor member for the hand grip;

Figure 8 is a perspective view of one of the cover members for the upper end of the hand grip;

Figure 9 is a sectional view of one form of connector fitting used on the end of the flexible link;

Figure 10 is a sectional view of a modified form of connector fitting;

Figure 11 is a sectional view showing a different manner of anchoring the upper end of the flexible cable link in the support member;

Figure 12 is a sectional view showing a modified form of anchor member for the hand grip;

Figure 13 is a perspective view of a modified form of shell member for the hand grip;

Figure 14 shows a combined anchor and housing member for supporting the hand grip;

Figure 15 is a horizontal cross sectional view taken on the line 15—15 in Figure 12;

Figure 16 is a horizontal cross sectional view taken on the line 16—16 in Figure 14; and

Figure 17 is a view with parts shown in section of a complete handle embodying features shown in various detail views.

In general, the invention comprises a hand grip member suspended by a link from a support member which may comprise a clamp or part of a clamp adapted for mounting on a horizontal rod or bar extending along the vehicle in an out-of-the-way position. In the preferred embodiments herein illustrated, the link comprises a short length of flexible steel cable having a ball connector fitting on one or both ends thereof to provide a flexible swivel and universal connection between the hand grip and the supporting

member. The cable link is preferably enclosed within a length of resilient tubular material which is mounted in end compression between the hand grip and the supporting member to prevent looseness of the parts and to prevent a passenger from grasping the cable itself. The tubular covering for the cable link also improves the appearance of the fixture and increases the stiffness of the link to some extent. By making the link from a piece of cable thus enclosed, it is still flexible but cannot be broken by bending, and by virtue of the swivel connection the hand grip may be freely twisted and articulated in all directions. The cable link, however, is preferably made quite short so that the hand grip cannot be wrapped around the support to exert an undue leverage on the parts. The present grab handle in the various forms illustrated is thus not only amply strong to support the dead weight of a person hanging on the strap, but is also unusually resistant to any efforts to cut, break, or dismantle the equipment.

Referring now to the drawings, the numeral 7 designates a horizontal pipe or rod which is usually mounted on brackets considerably higher than the heads of standing passengers. At intervals on this rod are clamped supports 8 for individual strap hangers having hand grips suspended within reach of the passengers by suspension members 9. The hand grip itself may take various forms as shown in Figures 2, 3 and 4. The numeral 10 designates an attractive form of hand grip made of a looped strip of tough, transparent, synthetic plastic material having a width and thickness providing ample stretch for this purpose.

The hand grip 11 in Figure 3 is similar to the grip 10, except that it is provided with a longitudinal internal cavity to receive a metal band 12. To facilitate bending of the hand grip to the shape shown, the plastic strip may be extruded with a central cavity to receive the reinforcing strip 12 loosely to provide for relative movement of the two strips in the bending operation. The strip 12 may, of course, be molded into the strip 11 as an integral part thereof if it can then be bent to the desired shape in that form.

The hand grip 13 in Figure 4 is made of aluminum tubing or the like, having flattened ends. Recognizing that the above and still other forms of hand grip are equivalent for the general purpose of the present invention, the device will be described with reference to the first mentioned grip 10 as this form of grip is illustrated in the other figures of the drawings.

The grip 10 is formed into a loop, as shown, having two ends 15 which are clamped between the arms of a U-shaped anchor member 16. A pair of channel-shaped shell or cover members 17 are applied to opposite sides of the member 16 to enclose both this member and the ends 15, and all of these parts are provided with a pair of holes 18 to receive a pair of special bolts and nuts 19, 19a, or other suitable securing means. When bolts and nuts are used, the nuts 19 have smooth circular heads which cannot be gripped by wrench or pliers, and after assembly the screw driver slots in the heads of the bolts 18 are preferably filled with solder to prevent unauthorized removal. Rivets may be used in place of the bolts and nuts 18, 19. The same fastening arrangement is used for the other types of handles shown in Figures 3 and 4. In the hand

grip 11 the spaced holes 18 are drilled through both strips 11 and 12 after bending.

In the preferred embodiment of the invention the suspension member, generally indicated at 8, embodies a link 20 which is preferably a short length of flexible steel cable. Affixed to the ends of this cable are swivel connector fittings 21 which may take various forms. The form of connector fitting shown in Figure 9 has a tapered bore 22 to receive the end of the cable and a relatively thin-walled neck or sleeve portion 23 extending for some length along the cable and adapted to be swaged tightly on the cable so that the cable will not pull out of the fitting under great tension. One end of the fitting is enlarged in the form of a partial sphere or ball to seat in an apertured socket in a support or anchor member.

Another form of connector fitting 21a is shown in Figure 10, having a hemispherical ball portion 24a formed on one end of a neck 23a which is adapted to fit the cable 20. The fitting 21a thus comprises a shell into which the end of the cable may be inserted in the manner shown with the various strands of the cable separated and spread apart in the cup of the hemispherical ball portion 24a. Molten solder 25 is then poured into the cup to anchor the fitting securely to the end of the cable.

The U-shaped anchor member 16 is provided with a generally hemispherical socket 26 to receive the ball end of the connector fitting and an aperture or opening 27 through which the neck portion of the fitting extends. The hemispherical socket 26 is preferably shaped to fit the ball end 24 or 24a on the connector fitting, and the opening 27 is preferably considerably larger in diameter than the neck portion 23 or 23a, so that the fitting not only can twist or swivel in the socket, but can also rock to a considerable angle in all directions to provide for limited universal movement as shown in Figure 6. The neck portion 23 or 23a of the connector fitting extends far enough along the cable to prevent the cable from being cut or worn by the edges of the opening 27 in any possible position of the parts.

In a similar manner, a connector fitting 21 or 21a on the upper end of the cable provides for suspension from the supporting member 8. The supporting member 8 comprises two mating and complementary semi-cylindrically grooved parts 29 and 30 adapted to be clamped together by bolts 31 or the like, to embrace and be supported by the pipe or rod 7, as shown. The under side of the part 30 of the supporting member is provided with a cavity forming a generally hemispherical socket 28 to receive the ball end of the connector fitting and an opening 32 for the neck of the fitting, the opening 32 being substantially larger in diameter than the neck of the fitting to permit both swiveling and limited universal movement of the fitting in the socket as shown in Figure 6.

In an alternative form of support member 30a shown in Figure 11, the upper end of the cable is anchored solidly in the support member, and then only the lower end of the cable is provided with a connector fitting 21 or 21a for swiveling and universal movement. In this embodiment the strands of the upper end of the cable are separated and spread out in the socket 33, and the latter is then filled with molten lead or other material to provide a firm anchor for the upper end of the cable, so that even under great ten-

sion it will not pull out of the support member. In this embodiment the opening 32a in the support member is preferably made to fit the cable, since there is not intended to be any movement between the cable and the support member. It is, of course, apparent that the upper end of the cable may be provided with a connector fitting 21 or 21a to swivel and have universal movement in the socket 28 as shown in Figure 6, with the lower end of the cable leaded in the socket 26 of the anchor member 16, but, in any event, the cable link 20 should have a connector fitting on at least one end for swiveling and universal movement. The ability of the connector fitting to swivel is more important than its universal movement because the cable itself is sufficiently flexible to bend without any universal movement in the connector fittings. It is necessary to have at least one swivel connection in the strap hanger between the hand grip 10 and the support 8 so that the cable strands will not be loosened or broken if the hand grip 10 is forcibly twisted.

In assembling the parts, a tough but resilient and flexible tubular protective member 35 is placed on the cable link 20 under considerable end compression between the supporting member 30 and the anchor member 16. At its upper end the tubular member 35 bears quite forcibly against the end of a boss 36 which contains the socket 28 and opening 32. At its lower end the member 35 bears forcibly against the outer surface of the rim of opening 27 and socket 26 in the anchor member 16, and may also bear against inturned flanges 37 on the cover members 17.

The compressed tubular member 35 has a number of functions. It covers the cable link 20 to prevent a person's hands from coming into contact with possibly broken strands in the cable. It prevents pinching of a person's hands between the neck of the connector fitting and the edge of the socket 26 or opening 27 if the hand grip is bent upwardly while in a person's grasp at that point. A still further and important function of the tubular covering 35 is to lend additional stiffness to the cable 20 so that it cannot be forcibly bent into a sharp kink which would damage the cable. If the hand grip 10 is recklessly or wantonly bent upwards with great force, as shown in Figure 6, there will be some angular movement at each of the connector fittings 21 and uniform bending throughout the length of the cable 20, but by making the tube 35 sufficiently thick and tough it will be impossible with human strength to kink the cable 20 to such a short radius that it would be damaged. In addition to the resistance to bending offered by the mere thickness and stiffness of the tube 35, it will be apparent that the additional longitudinal compression of this tube on the inside of the bend will further resist extreme bending. The relaxed length of the tube 35 before it is installed should be long enough so that when the grab handle is bent as shown in Figure 6 the end portions of this tube on the outside of the bend will not pull away from the boss 36 or rim of opening 27. Pinching or other injury to a person's hand or skin is thereby substantially prevented, even under rather extreme abuse of the equipment, and the equipment itself is rendered practically indestructible. The tube 35 may be rendered more resistant to cutting by reinforcing it with fabric or wire in a well known manner.

The compressed resilient tube 35 has a still 75

further function in holding the parts rather stiffly in a vertical position to prevent swinging or rattling of the strap hangers in a moving or jolting vehicle. The compressed condition of this tubular member normally holds the parts under tension to take up all slack in the connector fittings to prevent rattling, and so the desired swiveling and universal movements may be obtained without machining the surfaces by merely making the ball connector sockets large enough for a loose fit. Obviating machining and close tolerances reduces the cost of the parts.

The hand grip member may be mounted or anchored in different ways. Figures 12 and 15 show a modified form of construction which is particularly suited for use with the all plastic form of the hand grip 10 shown in Figure 2. The hand grip member 10 is a thick, flat strap of tough plastic material similar to the hand grip in Figure 5 except that the outer faces of the upper ends 40 are transversely grooved to provide a series of lugs 41 for supporting the strap in a modified form of U-shaped anchor member 42 having similar grooves to form co-mating and supporting shoulders 43. The upper end of the anchor member 42 is provided with a socket 26 for the ball end connector fitting 21 in the same manner as the previously described anchor member 16.

For convenience in assembling, the lugs 41 and shoulders 43 may be proportioned with respect to the thickness of the hand grip strip and the internal clearance in the anchor member so that the end portions 40 may be squeezed together and inserted into the bottom of the anchor member as a final step in the assembly of the whole device after the cable and its connector fittings and external sheath 35 have all been assembled. After the ends 40 of the hand grip have been inserted in the anchor member in the proper position for the lugs 41 to engage above the shoulders 43, a wedge or spacing member 44 is inserted between the ends 40 to spread them apart and maintain a secure interlocking grip between the tooth-like lugs and shoulders on the parts, as shown. Before insertion, the wedge 44 is preferably coated with some material to bond it to the grip member. Where the parts are made of synthetic plastic material, the wedge may be dipped in acetone or other solvent for the plastic which will form a strong bond when the wedge is pressed into place. The transverse lugs 41 and shoulders 43 may, of course, have other shapes to accomplish the purpose.

Figure 13 shows a modified form of housing 45 for the upper end of the hand grip to take the place of the two shell parts 17. When the one-piece housing 45 is used with the modification shown in Figure 12, the holes 18 may be omitted, since the bolts 19 are not used in this embodiment.

The one piece form of housing 45 shown in Figure 13 may be made to serve as the anchor member itself so that a separate anchor member 16 or 42 is not required. This is accomplished by making the housing 45 of heavier and stronger construction to constitute a strength member for suspending the hand grip from the link 20. In such case, the socket 26 is formed directly in the end of housing 45. The hand grip is then secured either by the use of bolts 19 through holes 18 in the housing, or by the provision of shoulders 43 in the housing to engage lugs 41 on the ends of the hand grip. One example of the latter form of construction is embodied in the anchor and

housing member 50 shown in Figures 14 and 16.

Figure 17 shows an embodiment of handle utilizing different forms of the parts shown in the detail views. The handle part 11 is the type shown in Figure 3, having an internal cavity for a metal reinforcing band 12. When the anchor member 16 and handle ends are drilled to receive the bolts 19 and these bolts are inserted as shown, the bolts independently support both the plastic and metal parts 11 and 12, so that it is not necessary to bond the plastic to the metal. Figure 13 shows a general view of the housing 45. The anchor for the cable 20 in the support 30a is described in connection with Figure 11.

Still other arrangements for securing the hand grip member, within the scope of the present invention, will occur to persons skilled in the art.

Having now described my invention and in what manner the same may be used, what I claim as new and desire to protect by Letters Patent is:

1. A street car grab handle and the like comprising a support, a flexible link having one end mounted in said support, a hand grip mounted on the other end of said link, and a flexible tubular protective sheath mounted on said link in end compression between said support and said hand grip.

2. A street car grab handle and the like comprising a support having a semicylindrical groove to be clamped on a cylindrical member, a socket in said groove, a hand grip, a link for suspending said hand grip from said support, means for mounting one end of said link in said socket, means for mounting the other end of said link in said hand grip, one of said mounting means comprising a ball and socket connection for limited universal movement, and a tubular protective sheath around said link.

3. A street car grab handle and the like comprising a support, a hand grip, a ball end flexible link for suspending said hand grip from said support, means for mounting one end of said link in said support, means for mounting the other end of said link in said hand grip; one of said mounting means comprising a socket for universal and swivel movement of said ball end, and a flexible tubular protective sheath around said link.

4. A street car grab handle and the like comprising a support, a hand grip, a flexible link for suspending said hand grip from said support, means for mounting one end of said link in said support, means for mounting the other end of said link in said hand grip, one of said mounting means comprising a swivel connection, and a resilient tubular protective sheath mounted on said link in end compression between said support and said hand grip.

5. A street car grab handle and the like comprising a support, a hand grip, a link for suspending said hand grip from said support, said link having one end mounted in said support and the other end mounted in said hand grip, one of said end mountings comprising a swivel ball connector on said link, and said connector having a protective neck portion forming a sleeve surrounding said link and extending for a distance along said link.

6. A street car grab handle and the like comprising a support member, a hand grip member, a link for suspending said hand grip member from said support member, means for mounting one end of said link in said support member, means for mounting the other end of said link in said

hand grip member, one of said mounting means comprising a ball connector on said link adapted for universal and swivel movement, and a protective sleeve on said ball connector surrounding said link to prevent said member from damaging said link.

7. A street car grab handle and the like comprising a support member, a hand grip member, a flexible cable link for suspending said hand grip member from said support member, means for mounting one end of said cable link in said support member, means for mounting the other end of said cable link in said hand grip member, one of said mounting means comprising a swivel connector integral with said link, a protective sleeve on said swivel connector extending along said cable link to prevent contact between said link and said member, and a flexible tubular protective sheath on said cable link.

8. A street car grab handle and the like comprising a support member, a hand grip member, a flexible cable link for suspending said hand grip member from said support member, and a resilient tubular sheath mounted on said cable link in end compression between said members to tension the parts and prevent kinking of said cable link.

9. A support member having an apertured socket, a hand grip member having an apertured socket, a link having a swivel ball connector fitting on each end thereof, each of said fittings being seated in one of said sockets and extending through the aperture thereof for limited universal movement.

10. A street car grab handle and the like comprising a support member, a hand grip member, an apertured socket in one of said members, a link having one end mounted in the other member, and a ball end connector fitting on the other end of said link and seated in said socket, said connector fitting having a reduced neck portion passing through said aperture with clearance to provide a universal and swivel connection between said link and said member.

11. A street car grab handle and the like comprising a support having an apertured socket, a hand grip having end portions clamped between the arms of a clamping member, an apertured socket in said clamping member, and a link having ball ends seated in said sockets and extending through said apertures.

12. A street car grab handle and the like comprising a support member having a semicylindrical groove and an apertured socket in one side of said groove, a hand grip member having an apertured socket, and a flexible suspending link having ball ends seated in said sockets and extending through said apertures.

13. A street car grab handle and the like comprising a support member having an apertured socket, a hand grip member having an apertured socket, a suspending link having opposite ball ends seated in said sockets and extending through said apertures, and a resilient tubular sheath mounted on said connector link in end compression between said members to prevent looseness of the parts.

14. In a street car grab handle and the like, a supporting member having a semicylindrical groove to fit a cylindrical member, means to clamp said supporting member on said cylindrical member; an apertured socket in said supporting member, a cable link having a ball end fitting seated in said socket and extending through said aperture, and a hand grip on said cable link.

15. In a street car grab handle and the like having a handle part suspended by a link from an overhead rod, a supporting member for the handle, said member having ends with means for clamping the member on the rod, a transverse groove in one side of the member at its mid portion between said ends to fit said rod, a socket cavity in said groove to receive an enlarged end on said link for limited universal movement, and an opening for said link in the opposite side of the member at its mid portion communicating with said socket cavity to accommodate the universal movement of the link.

16. In a street car grab handle and the like, a hand grip comprising a strip of plastic material constituting a strength member and having a longitudinal internal cavity, a metallic reinforcing strip in said cavity, an anchor member receiving the two ends of said strip, and means extending through transverse openings in said strips and anchor member to clamp the parts together and support said hand grip in the form of a loop of said plastic strip with both said plastic strip and said reinforcing strip individually supported by said means extending through said transverse openings.

17. In a street car grab handle and the like, a hand grip comprising a looped strip of material having end portions extending in the same direction, an anchor member for securing said end portions in side by side relation, lugs on said end portions, shoulders on said anchor member arranged to engage said lugs to anchor said hand

grip, and means insertable in the assembly of said anchor member and hand grip end portions for wedging said lugs and shoulders into tight engagement.

- 5 18. In a street car grab handle and the like, a hand grip comprising a looped strip of material having end portions extending in parallel relation, an anchor member receiving said end portions, lugs on the outer sides of said end portions, inwardly directed shoulders in said anchor member for engaging and supporting said lugs, and a member disposed between said end portions to spread said end portions apart and maintain the interengagement of said lugs and shoulders.
